UNITED STATES PATENT OFFICE.

WALTER FERRIS, OF MILWAUKEE, WISCONSIN, ASSIGNOR TO THE OILGEAR COMPANY, OF MILWAUKEE, WISCONSIN, A CORPORATION OF WISCONSIN.

HYDRAULIC BLANK HOLDER.

Application filed November 18, 1926. Serial No. 149,155.

This invention relates to hydraulic blank holders for draw presses.

Blank holders for this purpose ordinarily include a pressure ring which functions to apply the required gripping pressure to the blanks during the draw stroke and to strip the blank from the die during the return stroke. It is common practice to employ an air pad or springs for operating the pressure ring, but such devices are objectionable because of their inherent resiliency and the consequent jump that occurs at the instant the blank is freed from the die. Mechanical devices capable of positive action have been resorted to with a view to eliminating the jump, but such devices are not entirely satisfactory because of the complicated toggle movements ordinarily required to attain correct action of the ring. In my copending application Serial No. 115,487, filed June 12, 1926, I have described a hydraulic blank holder in which the above objections have been eliminated and which may be readily applied as a unit to standard types of presses without alteration. In the blank holder therein described however the blank gripping pressure is established by controlling the escape of liquid from the pressure cylinder during the draw stroke, and the resistance offered to this escape entails a waste of power and a consequent heating of the liquid.

One object of the present invention is the provision of a hydraulic blank holder so designed as to overcome the objections above noted.

Other more specific objects and advantages will appear from the following description of several embodiments of the invention.

In the drawings:

Figure 1 is a vertical sectional view of a blank holder constructed in accordance with the present invention and shown applied to a press of standard form.

Figs. 2 and 3 are similar views illustrating the positions of the parts during successive stages of a drawing operation.

Figs. 4 and 5 are similar fragmentary views of a blank holder of slightly different form, embodying the present invention.

Fig. 6 is a similar view of a third form of blank holder embodying the present invention.

The blank holder shown in Figures 1 to 3 comprises a pressure sustaining member in the form of a casting 10 supported beneath

the bed 11 of a press so as to move with the reciprocating ram 12. In this instance the casting 10 is carried by a pair of heavy rods 13, adjustably fixed at their lower ends to the casting and anchored at their upper ends in the ram 12. A piston 14 rigidly connected with and carried by the casting 10 is closely fitted for relative reciprocation within an appropriate cylinder 15, carried by a pressure plate 16, which is guided by the rods 13. Any appropriate means such as a stem 17, projecting upwardly from the cylinder 15 and threaded into the pressure plate 16, provides an adjustable connection between the plate and cylinder. The plate 16 is yieldably urged upwardly against the lower face of the bed plate 18 of the press by appropriate means such as springs 19, surrounding the rods 13 and interposed between the plate 16 and casting 10. The pressure plate 16 constitutes a support for the usual knock-out pins 20, guided for vertical reciprocation in the bolster 21 of the press, and supporting the usual pressure ring 22. The ring 22 surrounds the male die 23, fixed to the bolster 21, and cooperates with the female die 24, carried by the ram 12.

The cylinder 15 is maintained flooded with liquid from two sources. A reservoir 25 carried by the casting 10 and surrounding the cylinder 15 constitutes one source. A body of liquid, preferably oil, is maintained in this reservoir the liquid level being determined by the connection 26 with an appropriate overflow pipe 27. The cylinder 15 is provided with a series of inlet ports 28, open to the reservoir, and controlled by the piston 14. The piston in this instance is formed intermediate its ends, with an annular channel 29 which is always in open communication with the interior of the cylinder through appropriate ducts 30, and, at its upper end, with an appropriate peripheral shoulder 31, closely fitted in the cylinder and arranged to cover and thereby close the ports 28, when the piston and cylinder assume the positions shown in Figures 2 and 3.

Liquid is supplied to the cylinder 15 from a second source comprising a pump 32 preferably of a variable delivery type capable of delivering measured quantities of liquid to the cylinder. The pump shown is fully described in my prior Patent, No. 1,558,002, issued October 20, 1925. It will therefore suffice here to say that it is driven at constant

speed through appropriate means such as a pulley 33, and delivers liquid through a delivery pipe 34 at a definite rate determined by the setting of the control handle 35. The liquid is supplied from a sump provided in the base 36 of the pump casing. In this instance pipe 34 is connected to a passage 37 in the piston 14, leading to the interior of the cylinder 15, an appropriate relief valve 38 being provided for determining the maximum pressure within the delivery pipe. Appropriate swivel connections 39 are preferably provided in the supply pipe in order to permit free movement of the casting 10 to which the pipe is connected. The overflow pipe 27 is preferably connected to the sump in the base 36 of the pump casing through a flexible hose 40. The control handle 35 is ordinarily so adjusted as to cause the pump to deliver only very small quantities of liquid to the cylinder 15.

A brief description of a typical drawing operation will now be given. Figure 1 illustrates the relative positions of the parts prior to an operating cycle. The ram 12, and consequently the casting 10, are in elevated position, so that the dies 23 and 24 are separated, the ring 22 is in upper work receiving position, the pressure plate 16 bears against the lower face of the bed plate 18, and the piston 14 is disposed within the upper end of the cylinder 15, so that the interior of the cylinder is open to the reservoir 25 through ports 28, channel 29 and ducts 30. Then during the down stroke of the ram 12, the casting 10 moves downwardly therewith, but the pressure plate 16 remains in the elevated position shown until the upper die 24 engages the work, as indicated in Figure 2. This relative motion between the casting 10 and plate 16 produces a corresponding motion between the piston 14 and cylinder 15, causing the shoulder 31 of the piston to approach the ports 28 and to actually cover and close the same an instant before the die 24 engages the blank. During this relative motion between piston and cylinder, the cylinder has been maintained flooded by the admission of liquid from the reservoir 25 through ports 28, channel 29 and ducts 30 and from the pump 32 through the passage 37, and until the ports 28 are closed by the shoulder 31 the pressure in the cylinder does not exceed atmospheric pressure. After the ports are closed the pump continues to deliver liquid to the cylinder thereby immediately building up pressure therein to a degree dependent upon the setting of the relief valve 38. This increased pressure is transmitted thru the pressure plate 16 and pins 20 to the ring 22 to establish a blank holding pressure between the ring and the advancing die 24.

This clamping pressure is maintained during the continued down stroke of the ram 12,

die 24 and casting 10 until the drawing operation is completed, the ring 22, pins 20, and pressure plate 16 being forced downwardly by the advance of the die 24 during this period. Figure 3 illustrates the positions of the parts at the end of the draw stroke. It will be noted that during this draw portion of the stroke there is no relative motion between the piston and cylinder, so that the amount of liquid delivered by the pump need only be sufficient to maintain pressure within the cylinder against leakage losses.

During the upward or return stroke of the ram 12, die 24, and casting 10, the pressure is maintained in the cylinder 15, and the pressure plate 16, pins 20, and ring 22 are carried upwardly by the casting 10 until the pressure plate again engages beneath the bed plate 18. The ring 22 thus serves to strip the formed work piece from the lower die 23. The continued upward movement of the casting 10, after the pressure plate 16 has engaged the bed plate 18, forces the piston 14 upwardly into the cylinder 15 and the parts return to their respective positions shown in Figure 1. This upward movement of the piston again opens the ports 28 so that the liquid within the cylinder 15 is free to escape therethrough into the surrounding reservoir.

In the blank holder shown provision is made by which a greater pressure is available within the cylinder 15 during the stripping operation than during the draw stroke so as to obtain a greater stripping force. This is desirable because of the tremendous force sometimes found necessary to pry the work loose from the die. This is accomplished in this instance by interposing an appropriate check valve 41 in the pump delivery line between the relief valve 38 and passage 37. This valve prevents the escape of liquid from the cylinder to the valve 38, so as to trap the body of liquid within the cylinder 15 during the upward stroke of the casting 10. In order to relieve the cylinder of excessive pressures and to permit the required relative motion between the piston and cylinder to uncover the ports 28, when the pressure plate 16 strikes the bed plate 18 on the upward return stroke, a relief valve 42 is provided. This valve is connected to the passage 37 through an appropriate passage 43, and is ordinarily adjusted to open at a pressure considerably above the pressure at which the valve 38 will open.

The blank holder shown in Figures 4 and 5 is similar in many respects to that just described. It includes a pressure sustaining member in the form of a casting 10', supported beneath the bed 11 of the press by rods 13' fixed to the reciprocating ram of the press, and a pressure plate 16' supporting the usual knock-out pins 20'. In this in-

stance a piston 14' adjustably fixed to the pressure plate cooperates with a cylinder 15' carried by the casting, and the reservoir shown in Figures 1, 2 and 3 has been eliminated.

The cylinder shown in Figures 4 and 5 is supplied with liquid from a pump, such as that hereinabove described, through pipes 34' and 37', and an overflow pipe 27' leading 10 back to the pump determines the level of liquid within the upper open end of the cylinder. The piston 14' is provided with a peripheral channel 29' and shoulder 31' which cooperates with ports 28' in the cylinder wall 15 in a manner similar to that hereinabove described. In this instance each port 28' communicates through a pipe 44 with the upper end of the cylinder and through ducts 30' with the lower end of the cylinder. The 20 piston is preferably provided with a tail rod 45 of substantially the same diameter as the stem 17', so that the two sides of the piston are of substantially the same area, and the flow of liquid from one end to the other of 25 the cylinder, due to movements of the piston therein will not materially change the level of the liquid within the upper end of the cylinder. A check valve 41' is interposed between the pipes 34' and 37', and two relief 30 valves 38' and 42' are connected with pipes 34' and 37', respectively, which function in substantially the same manner as valves 38 and 42 hereinabove mentioned.

The arrangement is such that during the 35 downward idle stroke of the ram there is a relative motion between the piston 14' and cylinder 15' from the position shown in Figure 4 toward that shown in Figure 5. During this movement liquid is admitted to the lower 40 end of the cylinder through the pump delivery pipe 37' and the pipes 44 leading from the upper end thereof, until the ports 28' are closed by the shoulder 31' on the piston. This occurs as the reciprocating die strikes the 45 work and thereafter pressure is maintained within the cylinder, by the delivery of liquid thereto from the pump, thereby maintaining a blank gripping pressure during the entire draw stroke in a manner similar to that hereinabove described. During the return stroke 50 pressure is similarly maintained in the cylinder so as to effect a stripping operation, after which the piston and cylinder return to the positions shown in Figure 4.

The blank holder shown in Figure 6 is similar to that shown in Figures 1, 2 and 3 except that several sets of pistons 14" and 15" are employed. Two or more of such sets are ordinarily employed in those instances where 55 the blank is unusually large. The blank holder shown in this figure includes a single reservoir 25" carried by the casting 10" and surrounding the several sets of piston and cylinder assemblies. An overflow pipe 27" determines the liquid level in the reservoir.

The several cylinders are supplied from a single pump through a delivery pipe 34" and the passages 37" in each of the pistons. A check valve 41" and pressure relief valves 38" and 42" function in a manner similar to 70 the check valve 41 and relief valves 38 and 42 hereinabove described. The operation of the pistons and cylinders is substantially the same as that hereinabove described.

Various changes may be made in any of the 75 embodiments of the invention hereinabove described without departing from the invention as defined in the appended claims.

I claim:

1. In a draw press having cooperating 80 dies a blank holder therefor comprising a blank holding and stripping member cooperating with one of the dies to grip the blank therebetween, a pressure sustaining member connected with the last mentioned die, hydraulic means for transmitting pressure between said members, means responsive to relative movement between the dies for controlling said pressure during the draw stroke, and means for effecting an increased pressure 85 in said hydraulic means during the stripping operation.

2. In a draw press having fixed and movable dies a blank holder therefor comprising 90 a blank holding and stripping member cooperating with the movable die, a pressure sustaining member movable with the movable die, hydraulic means for transmitting pressure between said members, means responsive to movement of said movable die 95 for controlling said pressure during the draw stroke, and means for effecting an increased pressure in said hydraulic means during the stripping operation.

3. In a draw press the combination of a 100 relatively movable blank holding and stripping member and cooperating die, hydraulic pressure applying means associated therewith and normally operable to permit free relative movement therebetween, control means for said pressure applying means automatically operable to effect a clamping pressure between said die and member during the draw stroke, and means for effecting an increased pressure within said hydraulic 110 means during the stripping operation.

4. In a draw press the combination of a 120 relatively movable blank holding member and cooperating die, a pressure sustaining member connected with said die, a cooperating piston and cylinder between said members freely movable relative to each other during relative movement between said blank holding member and die, a liquid reservoir for maintaining a solid body of liquid in said cylinder during such movement, means operable to confine the liquid within said cylinder to thereby effect a working pressure therein during the draw stroke of the press 125 and a pump connected with said cylinder. 130

for maintaining said pressure against leakage losses.

5. In a draw press the combination of a relatively movable blank holding member and cooperating die, a pressure sustaining member connected with said die, a cooperating piston and cylinder between said members freely movable relative to each other during relative movement between said blank holding member and die, a liquid reservoir for supplying liquid to said cylinder, and a pump connected with said cylinder to establish a working pressure therein during the draw stroke of the press to thereby establish a work clamping pressure between said blank holding member and die during the draw stroke.

6. In a draw press the combination of a reciprocating ram, a pressure sustaining member movable with said ram, a blank holding member, a cooperating piston and cylinder between said members, a pump for delivering liquid at a predetermined rate to said cylinder, means for freely admitting and discharging liquid to and from said cylinder during the idle portions of the ram movements, and means for confining the liquid within said cylinder during the working portions of the ram movements to provide a working pressure therein.

7. In a draw press the combination of a bed plate, a reciprocating ram, cooperating dies on said plate and ram, a work holding and stripping ring, a pressure plate beneath said bed plate for supporting said ring, a pressure sustaining member beneath said pressure plate and carried by said ram, a cooperating piston and cylinder between said pressure plate and member freely movable during movement of said ram toward and from said ring, means for supplying liquid pressure to said cylinder to apply a blank holding pressure to said ring during the draw stroke of the ram and a check valve between said cylinder and said pressure sup-

ply means operable to confine the liquid in said cylinder during the stripping operation.

8. In a draw press having a pair of cooperating dies, a blank holding member cooperating with one of said dies to grip a blank therebetween, a pressure sustaining member connected with said last mentioned die, hydraulic pressure transmitting means between said members, a pump for delivering liquid at a predetermined rate to said means, and means for determining the fluid pressure in said pressure transmitting means.

9. In a draw press having a pair of cooperating dies, a blank holding member cooperating with one of said dies to grip a blank therebetween, a pressure sustaining member connected with said last mentioned die, hydraulic pressure transmitting means between said members, a pump for delivering liquid to said means, a check valve between said pump and said means, means for determining pump delivery pressure to thereby determine the blank gripping pressure, and separate means for determining the fluid pressure in said pressure transmitting means to thereby determine the blank stripping pressure.

10. In a blank holder for draw presses and the like comprising a blank holding member, a pressure sustaining member, a cooperating piston and cylinder between said members, means for delivering liquid to said cylinder, a port in said cylinder normally permitting a free admission and discharge of liquid to and from said cylinder, and said means, means controlled by movement of said piston for closing said port to thereby submit said piston and cylinder to the pressure of said liquid delivery means, and a pump for delivering liquid to said cylinder at a predetermined rate.

In witness whereof, I hereunto subscribe my name this 19th day of October, 1926.

WALTER FERRIS.
